UNITED STATES PATENT OFFICE.

JOHN CASAP, OF NEW YORK, N. Y.

FLYING-MACHINE.

1,032,812.

Specification of Letters Patent. Patented July 16, 1912.

Application filed October 4, 1911. Serial No. 652,690.

To all whom it may concern:

Be it known that I, JOHN CASAP, a citizen of the United States, and resident of New York, in the county of New York and 5 State of New York, have invented certain new and useful Improvements in Flying-Machines, of which the following is a specification.

This invention relates to flying machines 10 and its object is to provide a plane easily deflected but of such construction as to readily cleave the air and provide buoyancy for a platform or float.

Other means are provided in the invention 15 for adjusting the plane, steering the device and properly operating the motor for driving the fans as will be more fully described in the following specification, set forth in the claims and illustrated in the 20 drawings, wherein,

Figure 1 is a side elevation of an air ship constructed in accordance with this invention. Fig. 2 is a front view of same. Fig. 25 3 is a plan view with the plane removed. Fig. 4 is a detail view.

The device comprises a frame 10 of piping or any desirable like material with the necessary cross bracing 11, and in the upper end of the frame are bearings 12 in which 30 is journaled a bar 13 forming the main brace of the plane 14. This plane is adapted to tip at front or rear while swinging in the journaled bearings and the bar 13 is at suitable points provided with springs 15 to prevent 35 too sudden movement which might otherwise jar the device or permit of rapid movements which would cause the loss of control in emergencies.

The frame upon which the plane is built 40 is dished so as to form a convex structure and is made up of suitable bars and braces 16 to provide a substantial structure. It is also provided with a vertical bar 17 on which is hinged a rudder 18 controlled by 45 the arms 19 and cords 20 attached at their lower ends to a cross bar 21 and within reach of the operator so that by pulling one or the other of the cords, the rudder may be turned to one side or the other, the cross 50 arms 19 being pivoted near the bar 13 so that there is little or no slack in the cords 20 when the plane is tipped.

The plane 14 is operated by means of a chain 22 which is attached to the plane at 55 front and rear and passes over pulleys 23 then upward over a pulley 24 near the piv-

otal point of the plane so that no slack is permitted. The chain is operated by means of the hand wheel 25, located immediately in front of the seat 26, and at the lower end 60 of the shaft 27 which carries the hand wheel is a beveled gear 28 meshing with the pinions 29 and 30, the former connected by means of a chain 31 with a sprocket wheel 32 coupled with the wheel 23 which carries 65 and operates the chain 22. By turning the hand wheel 25 the operator may drive the chain 22 in either direction and tip the plane as may be desired in order to force the machine up or down while in the air.

The machine is driven by means of propellers 33, located at each side of the frame 10 and adapted to rotate on the side braces 34. Each propeller is provided with a sprocket wheel 35 which are both connected 75 by means of chains 36 with wheels 37 secured to the shaft 38 by means of the clutch 39 operated from the front of the machine by means of the lever 40 at one side of the 80 seat 26 and which throws the lever 41 of the clutch by means of a link 42.

The engine 43 may be of any desired type and be provided with the fly wheel 44 which may be also used to start the motor. The motor shaft 38 is journaled on a platform 45 85 at the rear end of which is a tank 46 for the fuel.

At each side of the frame 10 and to the forward bars is hinged side rudders 47 which are operated by means of laterally swinging 90 levers 48 beside the operator's seat. These levers are connected with the lower frame of the rudder by means of links 49 and may be quickly thrown in or out as the case may 95 demand.

In order to prevent the movement of the plane by high winds or by accident, brakes or pawls 50 are supplied and engage ratchet wheels 51 on shafts 30 which carry the pinion 52' and the pinion 29 so as to lock the 100 sprocket wheel 32 and prevent movement of the wheel 23 and the chain 22.

To each side of the plane is a guy rope 53 to brace the plane, and the frame is also provided with diagonal braces 54 to 105 strengthen same.

A brake 55 may also be provided having a band to encircle the brake wheel 56 on the forward axle 57, wheels 58 being provided to move the machine while on the surface. 110 These wheels and their axles are provided with springs 59 in order to provide flexibility

while the machine is being moved along the surface.

It is obvious that other arrangements of the parts may be provided for and modifications made if necessary without departing from the essential features above described.

What I claim as new and desire to secure by Letters Patent is,—

1. In a flying machine, the combination 10 with a platform mounted on wheels, of a frame rising from the platform, substantially vertical steering planes consisting of frames covered with fabric and hinged at the outside of the frame, a convex wire structure 15 covering the entire frame and platform, pivots securing the structure to the upper end of the frame, a chain connected at each end of the structure, pulleys carrying the chain, means for locking one of the pulleys, means 20 for turning the pulley, and propellers with motors for moving the machine.

2. In a flying machine, the combination 25 with a frame, of a seat on a platform, a convex plane made up of rods and covering and hinged on the frame, a chain connected with the front and rear of the plane and passing over sprocket wheels near the platform, a hand wheel in front of the seat, pinions operated by same and adapted to move one of 30 the sprocket wheels with the chain to tip the

plane, means for locking the pinions, propellers at the sides of the frame, a motor on the platform to operate the propellers, steering planes hinged on the outside of the frame, means for operating the steering 35 planes, and a rudder at the top of the frame.

3. In a flying machine, the combination with a platform mounted on wheels, of a frame rising from the platform, substantially vertical steering planes consisting of 40 frames covered with fabric and hinged to the main frame, a convex metal frame structure covering the platform and frames, pivots for the structure and working in the main frame, springs carried by the convex structure and 45 operating on the main frame to ease the tilting of the structure, chains attached to the front and rear of the structure, a hand wheel for operating the chains, sprocket wheels for carrying same, side rudders on the frame, 50 and levers near the hand wheel for swinging the rudders.

Signed at New York in the county of New York and State of New York this twenty-fifth day of September, A. D. 1911.

JOHN CASAP.
